UNITED STATES PATENT OFFICE

103,092

DESIGN FOR A BEDSTEAD

Rudolf Braun, Brooklyn, N. Y., assignor to Red Lion Table Company, Red Lion, Pa., a corporation of Pennsylvania

Application February 11, 1936, Serial No. 61,082

Term of patent 3½ years

To all whom it may concern:

Be it known that I, Rudolf Braun, a citizen of the United States, residing in the Borough of Brooklyn of the city of New York, in the State of New York, have invented a certain new, original, and ornamental Design for a Bedstead, of which the following is a specification, reference being had to the accompanying drawing, forming a part thereof.

The figure is a perspective view of a bedstead, showing my new design.

I claim:

The ornamental design for a bedstead, as shown.

RUDOLF BRAUN.
